UNITED STATES PATENT OFFICE.

JOHN K. RIDDLE, OF TOLEDO, OHIO, ASSIGNOR TO THE EDWARD N. RIDDLE COMPANY,
OF TOLEDO, OHIO, A CORPORATION OF OHIO.

LIGHTING FIXTURE.

Application filed July 18, 1924. Serial No. 726,692.

To all whom it may concern:

Be it known that I, JOHN K. RIDDLE, a citizen of the United States, residing at Toledo, in the county of Lucas, State of Ohio, have invented a certain new and useful Improvement in Lighting Fixtures, of which the following is a specification.

My invention relates to the construction described in my co-pending application, Serial No. 720,885, and has for its object to provide a different form of lighting fixtures which can be assembled without the necessity of employing any machine work in their construction, and to accomplish that result by means which will permit of the production of a highly ornamental fixture. It will not require any skilled labor in its assembly.

My means of accomplishing the foregoing objects may be more readily understood by reference to the accompany drawings, in which—

Fig. 1 is an elevation of a fixture constructed in accordance with my invention, part of the exterior being broken away to show the interior construction.

Fig. 2 is a cross-section taken on the line 2—2 in Fig. 1.

Fig. 3 is a cross-section taken on the line 3—3 in Fig. 1.

Figs. 4 and 5 are top and side detail view of the arms.

Figs. 6 and 7 are detail views of the notched disc.

Fig. 8 is a detail view of the conoidal member.

Fig. 9 is a detail view of the securing disc.

Fig. 10 is a detail view of the central spindle.

Fig. 11 is a detail view of the ornamental covering for the central spindle.

Similar reference numerals refer to similar parts throughout the entire description.

As shown in the drawings, the lighting fixture comprises a central spindle 1, which is provided with threads 2 and 3 at its lower and upper ends, respectively. A nut 4 is mounted upon the threads 2 at the lower end of the spindle. Upon this rests a spider 5, which is provided with a plurality of outwardly extending branches 6 terminating in sockets 7, to which may be secured the electric lights. These branches are channeled, as clearly seen in Figs. 1 and 3.

The branches 6 are provided with a central recess 32 in which is mounted a conoidal member 8, which is formed with a circumferential flange 9 and a shoulder 10, which is fitted to and extended into the central recess 32 in the body portion of the spider.

The conoidal portion 8 is provided with a central opening 11 at its upper end, through which the spindle 1 extends.

The spindle 1 is inclosed in an ornamental covering 12, which extends from the top of the conoidal member 8 to a notched disc 13. This disc, as clearly seen in Figs. 6 and 7 has a peripheral flange 14, in which are formed a plurality of notches 15.

A plurality of arms 16, in number corresponding to the number of branches 6, are then mounted upon the branches 6. These arms 16, as clearly seen in Figs. 1 and 5 are provided with downwardly extending lugs 17, which enter the channels in the branches 6 at a point adjacent the wall of the central recess, thereby completing this wall.

The curved portion 18 of the arm enters the channel, as clearly seen in Figs. 1 and 3. This serves to hold the arms against any latterly displacement. The lower end of the arm is then curved inwardly and upwardly forming a foot 19, the inner wall of which is fitted to and coincides with the surface of said conoidal member 8. The upper end 20 of the arm 16 is provided with an inwardly extending lug 21 which fits the slots 15 in the notched disc 13. The side of the wings 22 and 23 adjacent the wall of the notched disc are formed on an arc of the same radius as the inner surface of the peripheral flange 14 of the notched disc 13.

Above this notched disc is mounted a securing disc 25 which is provided with a shoulder 26, which engages the inwardly extending lugs 21, the flattened portion 27 resting upon the top of the said lugs. The securing disc 25 is provided with an upwardly extending portion 28, which is engaged by the bottom of loop 29, which is mounted upon the threads 3 on the upper end of the spindle 1.

The fixture is assembled in the following manner:

The nut 4 is fitted to the threads 2 on the spindle 1. Upon this is then mounted the spider 5, the wires 30 are then brought down through the center of the spindle and to a

hickey 31, of standard construction, whence they are carried out through the channels in the branches 6.

The conoidal member 8 is then placed in position, the shoulder 10 serving to hold it in position by engagement with the walls of the recess 32. The ornamental covering 12 is then placed in position. This serves to hold the spider and notched disc in spaced relation. The notched disc is dropped over the spindle 1 and rests upon the ornamental covering 12. The arms 16 are then placed in position by fitting the inwardly extending lugs 21 to the notches 15 in the notched disc 13. The lower curved portion of the arms 16 is placed in the branches 6, the lugs 17 entering into the channels in the branches 6, the lower curved portion of the arms also extends into the channels of the branches 6 and the foot 19 rests upon the outer tapered wall of the conoidal shaped member 8.

The securing disc 25 is then placed upon the spindle 1, the shoulder 26 serving to hold the wings tightly in engagement with the peripheral flange 14 in the notched disc, the flattened portion 27 preventing the lugs from moving upwardly and out of the notches. The loop 29 is then screwed upon the threads 3, and this serves to draw the parts together. The walls of the conoidal number 8 being tapered it is obvious that the more the loop is screwed down the tighter the foot 19 will be pressed against this conoidal member 8, and the more securely and rigidly the fixture will be held together.

It will be apparent from the foregoing description that there is not one particle of machine work required to assemble this fixture, with the exception of the threads on the spindle and the nut and loop there is no first-class machine work on the entire fixture.

The result of this construction is that I am able to provide a highly ornamental fixture at a very low cost of construction, and it will be obvious that the construction is not limited to the specific ornamental structure employed, but on the contrary a very wide number of designs can be made,—all of which will utilize my means of assembling, whereby the skilled labor required to manufacture a fixture can be done away with, and I do not desire to be understood as limiting myself to the specific details of construction or ornamentation, as obviously they form no part of my invention, and are furnished merely for the purpose of illustrating a preferred form for the utilization of my invention.

Having described my invention what I regard as new and desire to secure by Letters Patent is:

65 1. A lighting fixture comprising a central

spindle, a spider mounted at the lower end thereof, channeled branches on said spider, there being a central recess in the body portion of said spider, a conoidal shaped member mounted in said recess, a plurality of curved arms, lugs formed on said arms adjacent their lower ends, an inwardly extending foot portion on said arms fitted to the outer surface of said conoidal member, a notched disc at the other end of said spindle, lugs at the upper end of said arms which engage said notches, a securing disc on said spindle above said notched disc, a nut on each end of said spindle whereby the parts can be drawn tightly together and held rigidly in place.

2. A lighting fixture comprising a central spindle, a spider mounted at the lower end thereof, channeled branches on said spider, there being a central recess in the body portion of said spider, a conoidal shaped member mounted in said recess, a plurality of curved arms, lugs formed on said arms adjacent their lower ends, an inwardly extending foot portion on said arms fitted to the outer surface of said conoidal member, a notched disc at the other end of said spindle, lugs at the upper end of said arms which engage said notches, a securing disc on said spindle above said notched disc, an ornamental covering to hold said spider and notched disc in spaced relation, a nut on each end of said spindle whereby the parts can be drawn tightly together and held rigidly in place.

3. A lighting fixture comprising a central spindle, a spider mounted at the lower end thereof, channeled branches on said spider, there being a central recess in the body portion of said spider, a conoidal shaped member mounted in said recess, a plurality of curved arms, the lower curved portion of which being located in said channels, lugs formed on said arms adjacent their lower ends, an inwardly extending foot portion on said arms fitted to the outer surface of said conoidal member, a notched disc at the other end of said spindle, lugs at the upper end of said arms which engage said notches, a securing disc on said spindle above said notched disc, a nut on each end of said spindle whereby the parts can be drawn tightly together and held rigidly in place.

4. A lighting fixture comprising a central spindle, a spider mounted at the lower end thereof, channeled branches on said spider, there being a central recess in the body portion of said spider, a conoidal shaped member mounted in said recess, a plurality of curved arms, the lower curved portion of which being located in said channels, lugs formed on said arms adjacent their lower ends, an inwardly extending foot portion on said arms fitted to the outer surface of said

conoidal member, a notched disc at the other end of said spindle, lugs at the upper end of said arms which engage said notches, a securing disc on said spindle above said

5 notched disc, means to space said spider and notched disc, a nut on each end of said spindle whereby the parts can be drawn tightly together and held rigidly in place.

5. A lighting fixture comprising a central spindle, a spider mounted at the lower end thereof, channeled branches on said spider, there being a central recess in the body portion of said spider, a conoidal shaped member mounted in said recess, a plurality

of curved arms, the lower curved portion 15 of which being located in said channels, lugs formed on said arms adjacent their lower ends, an inwardly extending foot portion on said arms fitted to the outer surface of said conoidal member, a notched disc at 20 the other end of said spindle, lugs at the upper end of said arms which engage said notches, a securing disc on said spindle above said notched disc, means to space said spider and notched disc, a nut on each end of said 25 spindle whereby the parts can be drawn tightly together and held rigidly in place.

JOHN K. RIDDLE.
